(No Model.)

J. H. BICKFORD.
CAR TRUCK.

No. 466,595.

Patented Jan. 5, 1892.

UNITED STATES PATENT OFFICE.

JOHN H. BICKFORD, OF SALEM, MASSACHUSETTS.

CAR-TRUCK.

SPECIFICATION forming part of Letters Patent No. 466,595, dated January 5, 1892.

Application filed February 10, 1891. Serial No. 380,949. (No model.)

To all whom it may concern:

Be it known that I, JOHN H. BICKFORD, of Salem, county of Essex, State of Massachusetts, have invented an Improvement in Car-
5 Trucks, of which the following description, in connection with the accompanying drawings, is a specification, like letters and figures on the drawings representing like parts.

The prevailing tendency with street-rail-
10 way constructors at the present time is to em-
ploy cars much longer than formerly and car-
ried by two four-wheel trucks placed at or
near the opposite ends of the cars. Great
difficulty is experienced in securing trucks
15 for such cars, when driven by an electric mo-
tor, with a wheel-base sufficiently short to
pass around short curves on the track and at
the same time provide sufficient room between
the wheels in which to properly hang the elec-
20 tric motors. Great difficulty is also experi-
enced in obtaining sufficient tractive power
to propel these heavy cars, and one object of
this invention is to construct a swivel car-
truck in such a manner that without neces-
25 sarily increasing the actual weights of the
various parts such parts may be so arranged
that the effective weight thrown upon the
motor or driving wheels will be greatly in-
creased, producing a corresponding increase
30 in the tractive power of the car.

Another object of this invention is to pro-
duce a swivel car-truck which shall present
a very short wheel-base and at the same time
leave ample room for the motors and also
35 leave them at all times accessible for the re-
moval of armatures and other necessary re-
pairs. By the term "wheel-base" I mean the
space occupied by the wheels on the truck,
and therefore the closer the wheels of adja-
40 cent axles to each other the smaller the wheel-
base.

In carrying out this invention the side frame
of the truck is extended beyond the wheel-
base and carried across from one to the other
45 side to form a support for the armature end
of a motor, the opposite end of which may be
supported in usual manner upon one of the
axles. The weight of the car is taken upon
50 springs supported by the frame within the
wheel-base and placed preferably forward of
the middle in order to throw a greater pro-

portion of the weight of the car upon the mo-
tor-wheels, and as the motor is hung entirely
outside of the motor-wheels, which latter
therefore carry the entire weight of the motor 55
instead of only a portion of the weight of the
motor, as heretofore, a great increase of
weight is thrown upon the motor-wheels to
thereby increase the tractive power of the
car, and this without increasing the weight 60
of the several parts, and notwithstanding the
various parts are grouped in such a manner
as to bring an increased weight upon the mo-
tor-wheels. Such weight by my invention is
so distributed and balanced, as will be here- 65
inafter described, that the motor will receive
less severe shocks while running than trucks
constructed in accordance with the prevailing
type and carrying less weight upon their mo-
tor-wheels. The brake-rigging is placed be- 70
tween the wheels, the brake-shoes upon each
side of the truck being connected by toggle
levers, which when straightened will force the
brake-shoes apart against the wheels to apply
the brakes. The brake-rigging is so con- 75
structed that the less pressure applied to the
brake-shoes acting against the wheels carry-
ing the lightest load may be less than the
pressure applied to the wheels carrying the
greatest load, to thus prevent sliding a por- 80
tion of the wheels before the maximum brak-
ing pressure has been applied to the remain-
ing wheels.

Having thus stated generally the prin-
ciple of my invention, I will proceed now to 85
describe the best mode in which I have con-
templated applying that principle, and
will then particularly point out and distinctly
claim the part or improvement which I claim
as my invention.

Figure 1 represents in side elevation a por-
tion of one end of a double-truck car support-
ed upon a truck embodying this invention;
Fig. 2, a top or plan view, partially broken
away, of the truck shown in Fig. 1; and Figs. 95
3, 4, 5, and 6, details to be referred to.

Referring to the drawings, the wheels A,
mounted on the axles a, journaled in journal-
boxes a', may be of any usual form and con-
struction. The journal-boxes a' are embraced 100
by the housings b, between which and the
said journal-boxes are preferably interposed

pieces of rubber or other suitable yielding material, as shown at a^x , to take up the shocks. The housings b are connected by longitudinal beams or bars, said housings being herein shown as slotted at their upper sides to receive the parallel upper frame-bars c , extending continuously from one side around the end of the truck to the opposite side, as represented best in Fig. 2. The lower inner adjacent ends of the housings b are tied together by parallel lower frame-bars c' , (see Fig. 1,) and the housings at the front end of the truck are fitted to receive one end of the braces c^2 , extended obliquely upward to the upper frame-bar c , to which they are bolted. Diagonally-placed bars c^3 connect the upper and lower frame-bars between the housings, (see Fig. 1,) to stiffen and strengthen the construction. The usual guards G are supported by bars g , bolted to and carried by the housings b , as shown. The upper frame-bars c at the end of the truck are represented as united by bolts 2, firmly holding a block 3, through which is passed the suspension-bolt 5, encircled by the springs 10 12, the bolt being embraced between the springs by an ear or bracket m on the armature end of an electric motor M , supported at its opposite end on the axle a in usual manner. The armature m' (see Fig. 1) of the motor M is geared in usual manner to the axle a by the gear-wheels m^2 m^3 and m^4 m^5 , rotation of the armature turning the axle to move the car. The upper frame-bars c , on either side of the truck hold firmly between them blocks c^4 (shown in Fig. 3 and in section, Fig. 5,) which, together with the upper frame-bars c , support the preferably elliptic springs s , arranged in pairs upon either side of the frame, the springs of each pair being separated by a rib c^5 , raised on the block c^4 , and the springs are clamped or secured in place by the plates c^6 and bolts c^7 . (See Fig. 5.)

The bolster B , carried by the springs s , has a central bearing B' , in which rests and turns a corresponding bearing B^2 on the car-body H . (See Figs. 1 and 2.)

The springs s , which constitute the support for the car-body, are preferably placed somewhat forward of the transverse center of the truck and nearer the motor or driving axle and wheels, as shown, to thus throw a greater percentage of the weight sustained by the truck upon the motor or driving wheels to increase the tractive and driving power of the car. In practice the springs s will be inclosed in a housing h , suitably secured to the frame of the truck, and offset, as at h' , and cut away to receive and serve as a guide for the bolster B in its vertical movement. When starting the car, this housing will transmit the movement from the truck to the car-body, relieving the springs from all endwise pull or strain.

It has heretofore been customary to hang the motor within the wheel-base of the truck, in which case the weight of the motor is borne proportionately by the four wheels of the truck, and as the motor is usually applied to

only one pair of wheels of a swivel-truck a portion of the weight of the motor fails to be utilized to increase the tractive power, for the reason that such portion is sustained by the pair of wheels which are not geared to the motor. In the truck herein shown the motor is suspended or hung from the truck-frame entirely outside the wheel-base and beyond the motor-axle or the axle to which the power is applied, so that the entire weight of the motor is carried by the motor-wheels to thus increase the tractive power. In trucks as heretofore constructed probably not over two-thirds of the entire weight of the motor is carried by the motor-wheels, whereas in the truck herein shown the entire weight of the motor is carried by the motor-wheels, and as the motor usually weighs not less than three thousand pounds it will be evident that the additional one thousand pounds thus thrown upon the motor-wheels will greatly increase their tractive power. As previously set forth, where the motors are hung within the wheel-base of the truck the motors occupy so much room that it is almost impossible to bring the two pairs of wheels sufficiently near each other to permit the truck to easily pass curves of short radius; but with the improved truck herein described, as the motor is carried entirely outside the wheel-base the two pairs of wheels may be crowded as near together as necessary to pass a curve of any desired radius, and notwithstanding the wheels may be crowded close together, the motors, being upon the outside of the wheel-base, are always easily accessible for removal and repair. While the weight upon the motor-axle is thus greatly increased, it will be noticed that by placing the motor outside the wheel-base, whereby the increase in weight is obtained, the weight of the motor in such position tends to counterbalance the weight of the car supported upon the opposite side of the motor-axle, so that the action when passing an obstruction or unevenness in the rails is much easier and less severe upon the truck than where the motor is arranged within the wheel-base and acting together with the car-body as so much dead-weight.

The upper frame-bars c support the inwardly-projecting studs c^x , from which are hung the links e , to the lower ends of which are jointed the brake-shoes E , the brake-shoes upon the same side of the truck being connected by the links e' , jointed as represented at their adjacent ends to a bar e^2 , extended transversely across the truck, as shown. The links $e' e'$ form a sort of toggle-joint, and as the bar e^2 is lifted the links $e' e'$ are straightened to apply the brakes. The bar e^2 near its center has jointed to it a link e^3 , connected in turn at its upper end to one arm of a bell-crank lever e^4 , pivotally supported on the channel-bar e^5 , carried by the truck-frame, the other arm of the said bell-crank lever being jointed to one end of a bar or rod e^6 , operated in usual manner from the car-body to

apply the brakes. As the greater part of the weight of the car is carried on the front axle of each truck and the weight of the motors is also sustained thereon, it is evident that the wheels on those axles will permit a much more powerful application of the brake-shoes without sliding than will the inner wheels of the trucks, which do not sustain so great a weight. It follows, therefore, that where the brake-shoes are applied with a uniform pressure to all the wheels as by the ordinary brake-rigging, or even by a plain toggle arrangement, the wheels which sustain the lesser weight will slide long before the wheels which sustain the heavier weight will have received the maximum braking pressure. This sliding results in flattening the wheels, and to obviate this as far as possible I have constructed one of the links e' of each pair so that the brake-shoe operated thereby shall be applied with only sufficient pressure to secure the maximum efficient braking pressure, while the other brake-shoe may be applied by the same means at the same time with much greater effective pressure.

Referring to Figs. 1 and 6, the links e' , operating the brake-shoes which act upon the inner pair of wheels which support the lesser weight, are formed of two members 20 21, the adjacent ends of which slide within the sleeves 25, springs 26 interposed between them, as shown, tending to force said members apart. The sleeves 25 have two diametrically-opposite pins or studs 27, which move in the curved slots 28 in the brackets or frames 30, secured to or forming a part of the inner lower frame-bars c' . When the toggle-links e' are straightened, the force exerted acts to force both brake-shoes against their respective wheels with the same pressure until the same overcomes the strength of the spring 26, when the member 20 will be forced into the sleeve 25 and will compress the said spring until the shoulder 20 x comes into contact with the end of the sleeve, when the pressure previously resisted by the spring 26 will be taken by the pins or lugs 27 in the slots 28, and as the toggle is further straightened the entire force will be exerted upon the brake-shoes acting against the wheels carrying the greater weight. It will thus be seen when the spring 26 has been adjusted to limit the braking pressure upon its wheels that the moment the actuating force exceeds that limit the entire force or end-thrust afterward exerted will be received by the pins 27 and the bracket or support 30 and thrown upon the opposite brake-shoes.

I am aware that heretofore the motor has been placed outside of the wheel-base, but, so far as I know, in every such instance a rigid four-wheel truck is used and the car-body also is supported outside the wheel-base, so that no advantage results in the shape of counterbalancing or equalizing the two weights to lessen the severity of shocks received. In my invention I use a swiveled

four-wheel truck and support the motor outside the wheel-base and support the car-body within the wheel-base, and thereby the weight upon the motor-wheels is increased and their tractive power augmented, and at the same time the weights equalize one another to lessen the shocks.

I claim—

1. In a motor-car, the combination of the car-body, a four-wheel car-truck, a swivel connection for the two arranged nearer the pair of motor-wheels and within the wheel-base, and a motor hung between the truck-frame and motor-wheels axle outside the wheel-base, substantially as described.

2. In a motor-car, the car-body, bolster, and center-bearing plate thereon, and a four-wheel truck, its bolster and center-bearing plate, and interposed springs, the said bolsters, center-bearing plates, and springs being arranged out of center of the truck and nearer the motor-wheels and within the wheel-base, combined with a motor hung between the truck-frame and motor-wheels axle and outside the wheel-base, substantially as and for the purpose described.

3. In a motor-car, a swivel four-wheel car-truck having the car-body supported entirely within the wheel-base, and the motor hung outside the wheel-base and between the frame and motor-wheels axle, whereby the motor-wheels axle receives the weight, combined with a brake mechanism arranged between the pairs of wheels and adapted to impart greater resistance to the motor-wheels than to the others, in accordance with the greater inertia of the said wheels, substantially as described.

4. The combination, with the axles, wheels thereon, and journal-boxes therefor, of housings b for said journal-boxes, said housings being connected by parallel upper frame-bars c , and lower frame-bars c' , the upper frame-bars extending across the end of the truck from side to side to form a support for a motor outside the wheel-base, substantially as described.

5. A truck-frame consisting of housings for the journal-boxes having slots for the parallel upper frame-bars c and fitted to receive the lower frame-bars c' , and braces c^2 , substantially as described.

6. In a motor-car, a swivel four-wheel car-truck having the car-body supported entirely within the wheel-base, and the motor hung outside the wheel-base and between the frame and motor-wheels axle, whereby the motor-wheels axle receives the weight, combined with a brake mechanism arranged between the wheels and having its shoes supported by toggles, one member of said toggles being made with a yielding joint and limited as to movement and the other member having its movement unlimited save by the wheels and acting upon the motor-wheels of the truck proportionately with the superior inertia of such wheels, substantially as described.

7. The axles, wheels thereon, a truck-frame carried thereby, combined with brake-shoes suspended between said wheels, toggle-links connecting said brake-shoes, means to straighten the same, and a support to receive and take from one of the brake-shoes a portion of the end-thrust exerted by one of the links to force the said shoe against its wheel, substantially as described.
8. The axles, wheels thereon, a truck-frame carried thereby, combined with brake-shoes suspended between said wheels, toggle-links connecting said brake-shoes, means to straighten the same, one of the links having a spring introduced between it and the brake-shoe, and a support to receive the end-thrust of said link when said spring has been compressed, substantially as described.
9. The axles, wheels thereon, and a truck-frame carried thereby, combined with brake-shoes suspended between said wheels, and the links $e' e'$, connecting said brake-shoes, and means to straighten the same, one of said links consisting of two members 20 21, the sleeve 25, and spring 26, said sleeve having pins 27, adapted to move in the slot 28 in a support 30, all to operate substantially as described.
10. The axles, wheels thereon, a truck-frame carried thereby, combined with truck-shoes suspended to all against the said wheels, and

means whereby a limited pressure may be applied to a portion of said brake-shoes and a greater pressure to the remaining brake-shoes at the same time, substantially as described.

11. The combination, with the wheels and a truck-frame supported thereby, of springs supported by said truck-frame, a bolster connecting said springs, and a housing for said springs formed to serve as a guide for the bolster in its vertical movement, substantially as described.

12. In a swivel car-truck, the axles, wheels thereon, a truck-frame carried thereby, and a support for the car-body located entirely within the wheel-base, said support being out of the actual center of the truck and near to one pair of wheels, combined with a motor, one end of which is supported on one of the axles, its other end being supported by the truck-frame outside the wheel-base, and a brake-rigging placed between and adapted to act against the inner tread of the wheels, substantially as described.

In testimony whereof I have signed my name to this specification in the presence of two subscribing witnesses.

Corrections in Letters Patent No. 466,595.

It is hereby certified that in Letters Patent No. 466,595, granted January 5, 1892, upon the application of John H. Bickford, of Salem, Massachusetts, for an improvement in "Car-Trucks," errors appear in the printed specification requiring correction, as follows: In line 29, page 4, the compound word "truck-shoes" should read *brake-shoes*; and in line 30, same page, the word "all" should read *bear*; and that the said Letters Patent should be read with these corrections therein that the same may conform to the record of the case in the Patent Office.

Signed, countersigned, and sealed this 5th day of March, A. D., 1901.
